a corporation of Ohio

Original application June 30, 1945, Serial No.
602,596. Divided and this application January
5, 1949, Serial No. 69,332

13 Claims. (Cl. 204—321)

1

This application is a division of one filed June 30, 1945, entitled "Apparatus for Producing Vaporous Ozonides," Serial No. 602,596, now Patent No. 2,529,137, the present case having reference to the ozone generator incorporated in the apparatus of said patent.

An object of the instant invention is the production of a highly efficient and durable ozone generator of such simple construction that assembly, disassembly, and replacement of parts, when necessary, are greatly facilitated and require the minimum of time, the parts desirably interlocking in such fashion that they are held in assembled condition by a single fastening means.

Another and more specific object of the invention is to provide a construction by which the heat generating and/or heat absorbing parts of the ozone generator, such as the electrodes and dielectric, are kept at relatively low temperatures in order to preserve them against deterioration and prevent damage thereto and thus prolong their periods of usefulness, and this is accomplished by including means for admitting a volume of atmospheric air or other relatively cool gas to the ozone generator in excess of that which is to be ozonized, and conducting all of the air or gas in intimate heat exchanging relation to the aforesaid part or parts, the excess, over and above that ozonized, being vented to the atmosphere.

A further object is to include in the ozone generator, means for controlling the supply of air or other gas that is to be used for vaporizing purposes (and, more particularly, when atmospheric air constitutes such gas, for automatically stabilizing its temperature regardless of fluctuations in temperature of the atmosphere) so as to contribute to the production of a mixture of uniform proportions. This is accomplished in the present embodiment of the invention by means of a thermostatic control that is incorporated in the generator, and which properly apportions heated air and fresh atmospheric air in the production of an air supply of the desired temperature for vaporizing purposes.

These objects and advantages, with others hereinafter appearing, are attained in the embodiment of the invention illustrated in the accompanying drawings, wherein Fig. 1 is a sectional side elevation of an apparatus incorporating my improved ozone generator, the section being in offset planes, as indicated by the line 1—1 of Fig. 2, and passing centrally through the generator; Fig. 2 is a plan view of the apparatus with parts broken away, and Fig. 3 is a fragmentary

2

elevational view as though looking from the left of Figs. 1 and 2, the sectional portion of the view being in a plane indicated by the line 3—3 of Fig. 2.

5 Like reference characters designate like parts in the different views of the drawings.

Starting with a rather general description of the apparatus incorporating the ozone generator of the present invention, 1 denotes a base desirably constructed of sheet metal and having an upstanding peripheral flange 2. Rising from the base along a part of one side thereof is a panel 3 that is attached, by screws 4, to the flange 2. 5 is an electrical transformer of conventional 10 design that is attached to the top portion of the panel 3 by suitable fastening means, including bolts 6; and mounted on the base below the transformer is an air impeller or centrifugal blower 7, the fan of which (not shown) is driven by an 15 electric motor 8.

Fastened by screws 10 to the panel 3 is the rectangular housing 11 of an air conditioning unit—in the present instance, an air drier or dehydrator. For a more detailed description of the 20 same, reference may be made to the above application of which this is a division. The inclusion of this air conditioning unit is optional. The housing 11 has an air inlet, designated 12 in Fig. 1, that is placed in communicative connection 25 with the outlet of the air impeller or blower 7 through a conduit 13 (Fig. 2). On its side opposite the panel 3, and near its upper end, the housing 11 is provided with an air outlet 14.

An evaporating tank 15 is supported from the 30 base 1 by a stand 16. This evaporating tank is in the nature of a pan, closed at the top by a cover 17. A volatile liquid, such, for example, as pinene, is supplied to the evaporating tank from a dispensing receptacle 20. This receptacle may 35 consist of a glass bottle that rests in an inverted position within a suitable holder that surmounts the cover 17 of the evaporating tank so that the neck of the bottle depends through an opening in the cover and in such manner that the 40 discharge mouth of the receptacle or bottle will be liquid sealed within the tank, thereby to maintain, by the well-known barometric principle, a substantially constant liquid level in the tank at about the elevation indicated by the broken line 45 a in Fig. 1. This construction is disclosed in detail in the beforementioned application. Baffles 21 and 22, that extend from the cover 17 to well below the liquid level in the tank, provide a 50 tortuous course for the vaporizing gas, as will be seen by reference to the aforesaid application, as

well as to a division thereof, to wit: Serial No. 70,215, filed January 11, 1949, now abandoned.

An elongated mixing chamber 25 occupies a vertical position beyond one end of the evaporating tank 15, and is communicatively connected with the adjacent end of the tank, the connection between the tank and mixing chamber being indicated at 26 in Figs. 1 and 2. As will more fully appear hereinafter, ozone is delivered to the mixing chamber from the ozone generator and commingles with the vapors in said chamber, the resultant vaporous ozonide being discharged through an outlet opening 28 in the top wall of the chamber, shown in Fig. 2 as surrounded by a flanged collar 29.

Electrical current may be supplied in the usual way from a suitable source through conductors (not shown) to the electric motor 8, and to the primary coil of the transformer 5.

Surmounting the evaporating tank 15 and located alongside the mixing chamber 25 is the ozone generator designated generally by the reference numeral 30, and which I shall now describe in detail. Locked within an aperture of the cover 17 of the evaporating tank is an internally threaded boss 31 into which is screwed the lower threaded end of a hollow column 32 about which the parts of the ozone generator are assembled. It may be mentioned in passing, although it will be more fully explained hereinafter, that gas or air is delivered to the evaporating tank through the column 32.

Surrounding the lower end of the column 32 is a circular bottom unit 33 having an annular base flange 34 that bears, through a similarly shaped pad 35, on a slightly elevated part of the cover 17. A part of the unit 33, outwardly beyond the flange 34, is frusto-conical; and the peripheral portion of said unit is enlarged vertically and contains an upwardly facing channel 36. The inner and outer walls 37 and 38 of the channel are spaced further apart at the top than they are at the bottom of the channel, and formed on the inner sides of said walls adjacent their upper edges are annular seats wherewith are engaged the lower ends of the inner and outer cylindrical casing walls 40 and 41, respectively. These casing walls are made of suitable metal and are provided a short distance above their lower ends with series of vent apertures, those of the respective inner and outer walls being designated 40^a and 41^a. Applied to the top of the inner wall 40 is a circular partition 43, having openings 43^a, the partition being properly positioned with respect to said wall by a depending flange 44. A cross pin 45 is extended through diametrically opposed holes in the column 32 and has its ends confined within a central depression of the partition 43 and with the partition thus held down, it serves to retain the wall 40 with its lower end firmly engaged with the seat upon which it bears.

Fitted over the top of the outer cylindrical wall 41 is a flanged rim of a two-part cap or top unit 50, the parts whereof separate in substantially the central horizontal plane of the unit. The mating edges of the two parts are formed with interfitting flanges to more effectively close the joint between said parts. Projecting through a central aperture in the circular top wall 51 of the unit 50 is the threaded upper end of the column 32, and applied to said end is a screw cap 53 that bears against said wall and presses the entire assembly surrounding the

column downwardly against the cover 17 of the evaporating tank 13.

Disposed between the inner and outer cylindrical casing walls 40 and 41 in substantially concentric spaced relation thereto and to one another, are inner and outer tubular electrodes 55 and 56, respectively, and, intermediate the two electrodes, a dielectric 60. According to my present preference, stainless steel is used for the electrodes, and boro-silicate glass, generally known by the trade name "Pyrex," for the dielectric. The electrodes bear at their lower ends on a plurality of lugs 61 that are spaced apart about the channel 36 and are carried by the inner and outer walls thereof, the upper ends of said lugs being notched to provide seats for the electrodes. The dielectric extends a substantial distance below the lower ends of the electrodes and is shown as yieldingly supported by a suitable number of resilient clips 63 that are distributed about the channel 36 and rest on the bottom wall thereof and serve to sustain the dielectric substantially equally spaced from the two electrodes.

A header 65, in the form of a downwardly opening annular channel, is applied to the upper ends of the electrodes and dielectric. The outer electrode 56 is flared adjacent its upper end and seats within the rabbeted lower edge of the outer wall of the header 65, while the upper end of the inner electrode is contracted and seats within the rabbeted lower edge of the inner wall of the header. The dielectric extends well above the tops of the electrodes and is yieldingly located substantially centrally within the channel of the header by a series of resilient clips 68. The header is provided with a lateral outlet extension 70 that projects through an aperture that is divided between the two parts of the top unit 50 and is approximately aligned with a neck 71 that surrounds the ozone inlet opening of the mixing chamber 25. A gas-tight joint between said extension 71 and the neck 70 is made by a coupling 73 of suitable resilient material. The ends of the coupling, after being stretched over the circumferentially beaded ends of the extension and neck, contract and snugly fit about said parts. The header 65 is spaced from the top wall 51 of the unit 50 by lugs 75 on the header, and from the peripheral wall of said unit by lugs 76 that extend inwardly from the last mentioned wall.

Air or gas is admitted to the casing of the ozone generator from the housing 11 of the air conditioning unit through a relatively large opening 80 in the outer casing wall 41. The flared end of a fitting 81 is welded or otherwise secured to said wall 41 about the opening 80, while its end remote from said wall is provided with an opening surrounded by a flange 82 into which a flange surrounding the outlet 14 of the housing 11 snugly fits.

It may be explained, though not illustrated, that one terminal of the secondary winding of the transformer 10 is grounded. The other terminal, represented by a binding post 83, is electrically connected, through a conductor 85, with the inner electrode 55 of the ozone generator, said conductor entering the casing of the generator through a hole 86 in the top wall of the unit 50. The outer electrode 56 is grounded through a spring finger 87 of suitable metal that is carried by the outer casing wall 41 and bears against said electrode.

An annular partition 90 divides the space that

is enclosed by the inner casing wall 40, the bottom unit 33 and the previously mentioned partition 43, into a cool air chamber 91 and a warm air chamber 92. The interior of the hollow column 32 communicates with the cool air chamber 91 through a port 93 in the wall of said column, and with the warm air chamber 92 through a port 94. A thermostatic element 95, in the form of a bi-metal strip, is carried by a bar 96 that extends across and is supported by the column. Valves or shutters 97 and 98 are carried by the bi-metal strip near the free end thereof and are arranged to cooperate with the respective ports 93 and 94. Under the influence of abnormally cool air, the bi-metal strip warps in a direction to move the valve or shutter 97 toward the port 93, and, under the influence of warm air, in a direction to move the valve or shutter 98 toward the port 94.

In operation, with electric current supplied to the motor 8 and transformer 5, air will be delivered by the impeller or blower 7, through the housing 11, to the interior of the ozone generator casing, the air entering said casing through the opening 8. A part of the air flows upwardly within the annular space between the outer casing wall 41 and the adjacent electrode 56 and finds its way about the header 65, located within and spaced from the walls of the top unit 50, the air continuing downwardly between the inner casing wall 40 and the adjacent electrode 55. Some of this air enters the cool air chamber 91 through the openings 43^a in the partition 43. The remainder of the air entering through the opening 8 descends within the annular space first above mentioned and flows into the channel 36 of the bottom unit 33 and thence through the ozone generating space between the outer electrode 56 and the dielectric 60. Some of this downwardly flowing air may pass around the lower end of the dielectric and join the air descending between the inner electrode 55 and the adjacent casing wall 40 to ascend therewith through the ozone generating space between the inner electrode and the dielectric. The ozone generated in the spaces on opposite sides of the dielectric 60 is collected within the header 65 from which it passes through the extension 70 and neck 71 into the mixing chamber 25.

Attention is called to the fact that all air admitted to the apparatus enters the ozone generator casing. All of this air, or, in any case, a very large percentage of it, serves to cool the heat generating and heat absorbing parts of the apparatus, particularly the electrodes 55 and 56 and the dielectric 60. A part of the air, after serving such purpose, escapes to the atmosphere, as will be more fully explained hereinafter. Another part continues on through the ozone generating spaces, and is ozonized and delivered to the mixing chamber, as set out above, while the remainder is conducted to the evaporating tank for producing vapors from the volatile liquid therein and, laden with said vapors, passes on to the mixing chamber where it joins the before-mentioned ozonized air, the two parts now under consideration being thoroughly intermingled in said chamber and discharged therefrom through the opening 28.

It is important that a proper balance be maintained between the main constituents of the vaporous ozonide, and while this may be accomplished in large measure by providing passages of predetermined capacity for the ozone and vapors, I promote the desired end, according to the

herein disclosed embodiment of the invention, by employing the beforementioned thermostatic means comprising the bimetal strip 95 and the valves or shutters 97 and 98. In considering the manner in which this automatic control functions, it will be assumed that the atmospheric temperature is low and that the air entering the ozone generator through the opening 80 is too cold to properly vaporize the liquid in the evaporating tank 15. The air entering the cool air chamber 91 through the openings 43^a passes into the hollow column 32 through the port 93 and strikes the bi-metal strip 95. The resultant chilling of the strip causes it to warp in the direction to present the valve or shutter 97 to the port 93 and wholly or partially close the port. In the meantime, air passing downwardly between the inner casing wall 40 and the adjacent electrode 55 is heated and a part of it enters the warm air chamber 92 through the apertures 40^a. Some of this warm air passes through the port 94 into the hollow column 32 and is conducted thereby into the evaporating tank 10, such air being warm enough to vaporize the liquid and, with the vapors, passes on to the mixing chamber. Air admitted to the chamber 92 in excess of that delivered to the evaporating tank escapes to the atmosphere through openings 33^a of the bottom unit 33.

Under continued operation of the apparatus, the air that enters the warm air chamber 92 might become heated to such a degree that unless its temperature were moderated it would produce an over-amount of vapor, causing a preponderance of the pinene or other treatment in the final product. This is avoided by response of the thermostatic means to the overly warm air, the bi-metal strip 95 now warping in the reverse direction to that before mentioned, thus opening the port 93 to admit cool air to the column. This cool air, mixing with the heated air, provides a supply to the evaporating tank 15 of a temperature to generate the proper amount of vapor. Any rise in the atmospheric temperature will result in the bi-metal strip warping further in the present direction to close or partially close the port 94 and shut down the supply of heated air.

As previously explained, the inclusion of the air conditioning unit comprising the housing 11 is optional. When said unit is omitted, direct communicative connections are made between the air impeller or blower 7 and the opening of the fitting 81, as fully disclosed in the parent application.

Having thus described my invention, what I claim is:

1. An ozone generator structure comprising an inner tubular electrode, an outer tubular electrode, and an interposed tubular dielectric, all arranged in substantially concentric, spaced relation to one another, an outer wall surrounding and slightly spaced from the outer electrode, a tubular inner wall similarly spaced from the inner electrode, a header to which the upper ends of the electrodes are joined and into which the upper end of the dielectric projects, the header enclosing an ozone passage into which the spaces on the opposite sides of the dielectric open, a hollow bottom unit to which the lower ends of the aforesaid walls are joined and within which are disposed the lower ends of the electrodes and the dielectric, the unit comprising an enclosing wall from which the lower ends of the electrodes are spaced, thereby to provide by

reason of such spacing communication between the spaces on the opposite sides of each electrode, a cap enclosing and spaced from the header and having its lower end joined to the aforesaid outer wall, and means for admitting gas to the space enclosed by the outer wall and cap.

2. An ozone generator structure comprising a hollow column, an inner tubular electrode, an outer tubular electrode, and an interposed tubular dielectric, all arranged in substantially concentric, spaced relation to one another and to said column, an outer wall surrounding and slightly spaced from the outer electrode, an inner wall surrounding the column and similarly spaced from the inner electrode, a partition extending between said inner wall and the column, the column being apertured to provide communication between the interior of the column and the spaced above said partition, a header to which the upper ends of the electrodes are joined and into which the upper end of the dielectric projects, the header enclosing an ozone passage communicating with the spaces on the opposite sides of the dielectric, a hollow bottom unit surrounding the base of the aforesaid column and to which the lower ends of the aforesaid walls are joined and within which are disposed the lower ends of the electrodes and the dielectric, the unit comprising an enclosing wall from which the lower ends of the electrodes are spaced, thereby to provide by reason of such spacing communication between the spaces on the opposite sides of each electrode, a cap enclosing and spaced from the header and having its lower end joined to the aforesaid outer wall, means securing said cap to the top of the column, and means for admitting gas to the space enclosed by the outer wall and cap.

3. An ozone generator structure according to claim 2, wherein the outer wall is apertured for venting purposes adjacent its lower end.

4. An ozone generator structure according to claim 2, wherein the inner wall is apertured for venting purposes adjacent its lower end, and said bottom unit is apertured for like purposes.

5. An ozone generator structure comprising a hollow column, an inner tubular electrode, an outer tubular electrode, and an interposed tubular dielectric, all arranged in substantially concentric, spaced relation to one another and to said column, an outer wall surrounding and slightly spaced from the outer electrode, an inner wall surrounding the column and similarly spaced from the inner electrode, an apertured partition extending between the top of said inner wall and the column, the column having an opening below said partition, a header to which the upper ends of the electrodes are joined and into which the upper end of the dielectric projects, the header enclosing an ozone passage into which the spaces on the opposite sides of the dielectric open, a bottom unit surrounding the base of the aforesaid column and to which the lower ends of the aforesaid walls are joined and within which are disposed the lower ends of the electrodes and the dielectric, the unit comprising an enclosing wall from which the lower ends of the electrodes are spaced, thereby to provide by reason of such spacing communication between the spaces on the opposite sides of each electrode, a cap enclosing and spaced from the header and having its lower end joined to the aforesaid outer wall, means securing said cap to the top of the column, and means for

admitting gas to the space enclosed by the outer wall and cap.

6. An ozone generator structure comprising a hollow vertically disposed column, an inner tubular electrode, an outer tubular electrode, and an interposed tubular dielectric, said electrodes and dielectric surrounding the column and being arranged in substantially concentric spaced relation to one another and to said column, an outer wall surrounding and slightly spaced from the outer electrode, an inner wall similarly spaced from the inner electrode, a header to which the upper ends of the electrodes are joined and into which the upper end of the dielectric projects, the header enclosing an ozone passage into which the spaces on the opposite sides of the dielectric open, a bottom unit surrounding the base of the aforesaid column and to which the lower ends of the aforesaid walls are joined and within which are disposed the lower ends of the electrodes and dielectric, said bottom unit having a central opening that receives the lower end of the column and the unit comprising an enclosing wall from which the lower ends of the electrodes are spaced, thereby to provide by reason of such spacing communication between the spaces on the opposite sides of each electrode, a cap enclosing and spaced from the header and having its lower end joined to the aforesaid outer wall, means securing said cap to the top of the column, means for admitting air to the space enclosed by the outer wall and cap, the aforesaid header having an outlet leading from the ozone passage thereof, a partition surrounding the column and extending therefrom to the aforesaid inner wall intermediate the ends of the latter so as to separate the interior of said inner wall into a cool air space above said partition and a warm air space below the partition, said inner wall being apertured below the partition, a cool air port in said column above said partition, a warm air port in said column below the partition, a thermostatic element supported within the column, and shutter means operatively connected thereto for controlling the passage of air through said ports.

7. An ozone generator structure comprising a hollow vertically disposed column, an inner tubular electrode, an outer tubular electrode, and an interposed tubular dielectric, said electrodes and dielectric surrounding the column and being arranged in substantially concentric spaced relation to one another and to said column, an outer wall surrounding and slightly spaced from the outer electrode, an inner wall similarly spaced from the inner electrode, a header to which the upper ends of the electrodes are joined and into which the upper end of the dielectric projects, the header enclosing an ozone passage into which the spaces on the opposite sides of the dielectric open, a bottom unit surrounding the base of the aforesaid column and to which the lower ends of the aforesaid walls are joined and within which are disposed the lower ends of the electrodes and dielectric, said bottom unit having a central opening that receives the lower end of the column and the unit comprising an enclosing wall from which the lower ends of the electrodes are spaced, thereby to provide by reason of such spacing communication between the spaces on the opposite sides of each electrode, a cap enclosing and spaced from the header and having its lower end joined to the aforesaid outer wall, means securing said cap to the top of the column, means for admitting

air to the space enclosed by the outer wall and cap, the aforesaid header having an outlet leading from the ozone passage thereof, a partition surrounding the column and extending therefrom to the aforesaid inner wall intermediate the ends of the latter so as to separate the interior of said inner wall into a cool air space above said partition and a warm air space below the partition, said inner wall being apertured below the partition, a cool air port in said column above said partition, a warm air port in said column below the partition, a bi-metal strip, a cross bar in the column to which one end of said strip is secured, the aforesaid ports being on opposite sides of the column, and shutters secured to the opposite sides of said strip for cooperation with said ports.

8. In an ozone generator, an inner tubular electrode, an outer tubular electrode, an interposed tubular dielectric, and a tubular casing wall surrounding the outer electrode, all of the foregoing elements being arranged in substantially concentric, spaced relation to one another, a bottom unit applied to the lower end of the casing wall, said bottom unit including an upwardly opening annular channel into which the lower end of the dielectric extends, the lower edge of the casing wall engaging the outer wall of the channel, seats spaced apart about the inner and outer walls of the channel for supporting the electrodes with their lower ends adjacent the top of the channel, a header in the form of a downwardly opening channel fitted to the upper ends of the inner and outer electrodes and into which the corresponding end of the dielectric extends, a cap enclosing said header and applied to the upper end of the casing wall, the header having an outlet for ozonized fluid, means binding the cap to the bottom unit to thereby clamp between the cap and unit the casing wall, with the electrodes, header and dielectric held in operative relation to one another, and means for admitting air to the space enclosed by the casing wall, cap and bottom unit.

9. An ozone generator according to claim 8, wherein the cap includes a top wall and a peripheral wall, and means are provided for spacing the header from said walls of the cap.

10. In an ozone generator, an inner tubular electrode, an outer tubular electrode, an interposed tubular dielectric, and a tubular casing wall surrounding the outer electrode, all of the foregoing elements being arranged in substantially concentric, spaced relation to one another, a bottom unit applied to the lower end of the casing wall, said bottom unit including an upwardly opening annular channel into which the lower end of the dielectric extends to substantially the bottom of the channel, the lower edge of the casing wall engaging the outer wall of the channel, seats spaced apart about the inner and outer walls of the channel for supporting the electrodes with their lower ends adjacent the top of the channel and in spaced relation to the sides thereof, a header in the form of a downwardly opening channel fitted to the upper ends of the inner and outer electrodes and into which the corresponding end of the dielectric extends, a cap enclosing said header in spaced relation thereto and applied to the upper end of the casing wall, the header having an outlet extension, and the cap having an aperture through which said extension projects, means binding the cap to the bottom unit to thereby clamp between the cap and unit the casing wall, with the elec-

trodes, header and dielectric held in operative relation to one another, and means for admitting air to the space enclosed by the casing wall, cap and bottom unit.

11. In an ozone generator, an inner tubular electrode, an outer tubular electrode, an interposed tubular dielectric, and a tubular casing wall surrounding the outer electrode, all of the foregoing elements being arranged in substantially concentric, spaced relation to one another, a bottom unit applied to the lower end of the casing wall, said unit including an upwardly opening annular channel into which the lower end of the dielectric extends a substantial distance, the lower edge of the casing wall engaging the outer wall of the channel, seats spaced apart about the inner and outer walls of the channel for supporting the electrodes with their lower ends adjacent the top of the channel and in spaced relation to the sides thereof, a header in the form of a downwardly opening channel fitted to the upper ends of the inner and outer electrodes and into which the corresponding end of the dielectric extends, a cap enclosing said header and applied to the upper end of the casing wall, the header having a fluid outlet, an elongated element extending axially of the inner electrode and to the opposite ends of which the bottom unit and cap are secured, the casing wall being clamped between the cap and unit with the enclosed electrodes, dielectric and header held in operative relation to one another, and means for admitting air to the space enclosed by the casing wall, cap and bottom unit.

12. In an ozone generator, an inner tubular electrode, an outer tubular electrode, an interposed tubular dielectric, and a tubular casing wall surrounding the outer electrode, all of the foregoing elements being arranged in substantially concentric, spaced relation to one another, a bottom unit applied to the lower end of the casing wall, said bottom unit including an upwardly opening annular channel into which the lower end of the dielectric extends, the lower edge of the casing wall engaging the outer wall of the channel, seats spaced apart about the inner and outer walls of the channel for supporting the electrodes with their lower ends adjacent the top of the channel and in spaced relation to the sides thereof, a header in the form of a downwardly opening channel fitted to the upper ends of the inner and outer electrodes and into which the corresponding end of the dielectric extends, a cap enclosing said header in spaced relation thereto and applied to the upper end of the casing wall, the header having an outlet for the ozonized fluid, and means binding the cap to the bottom unit to thereby clamp between the cap and unit the casing wall, with the electrodes, header and dielectric held in operative relation to one another, the casing wall having an opening for admitting air to the space enclosed by the casing wall, cap and bottom unit.

13. In an ozone generator, an inner tubular electrode, an outer tubular electrode, an interposed tubular dielectric, and a tubular casing wall surrounding the outer electrode, all of the foregoing elements being arranged in substantially concentric, spaced relation to one another, a bottom unit applied to the lower end of the casing wall, said unit including an upwardly opening annular channel into which the lower end of the dielectric extends, the lower edge of the casing wall engaging the outer wall of the channel, seats spaced apart about the inner and

outer walls of the channel for supporting the electrodes with their lower ends adjacent the top of the channel and in spaced relation to the sides thereof, a header in the form of a downwardly opening channel fitted to the upper ends of the inner and outer electrodes and into which the corresponding end of the dielectric extends, a cap enclosing said header and applied to the upper end of the casing wall, the header having an outlet for ozonized fluid, a hollow column disposed axially of the inner electrode and to the upper and lower ends of which the cap and bottom unit are, respectively, secured, the bottom unit having an aperture through which the lower end of the column projects, the column being apertured for the entrance of air thereto intermediate the cap and bottom unit, and means for admitting air to the space enclosed by the casing wall, cap and bottom unit.
